UNITED STATES PATENT OFFICE.

JOHN HAYS HAMMOND, JR., OF GLOUCESTER, MASSACHUSETTS.

SMOKE PRODUCER.

Application filed October 17, 1917, Serial No. 197,125. Renewed October 25, 1921. Serial No. 510,288.

To all whom it may concern:

Be it known that I, JOHN HAYS HAMMOND, Jr., a citizen of the United States, residing in Gloucester, in the county of Essex and State of Massachusetts, have invented certain new and useful Improvements in Smoke Producers, of which the following is a specification.

Some of the objects of this invention are 10 to provide in a smoke producer improved means controlled from a distance for varying the amount of air admitted to the producer to vary the amount of smoke produced; to provide in a smoke producer improved means for controlling the draft of 15 the producer to vary the amount of smoke delivered; to provide in a smoke producer improved means controlled from a distance for mixing chemicals or materials in such 20 a manner as to produce quickly a dense volume of smoke; and to provide other improvements as will appear hereinafter.

In the accompanying drawings, Fig. 1 is a diagrammatic side elevation partly in 25 vertical section of a smoke producer constructed in accordance with this invention and arranged to be controlled in response to electroradiant energy; Fig. 2 is an enlarged fragmentary side elevation of a detail of 30 the same; and Figs. 3 and 4 are vertical sections of two modified forms respectively of this invention.

Referring to the drawings, and particularly to Fig. 1, one embodiment of this 35 invention comprises a smoke producer which includes a hollow, stationary combustion chamber 10 which is constructed to hold in the lower portion thereof smoke producing material 11. The chamber 10 is provided 40 at one end with a chimney or outlet 12 communicating therewith and is provided at its other end with a gasolene burner 13 which projects inwardly and downwardly through the end wall of the chamber and which is 45 arranged to be supplied with gasolene or other liquid fuel through a pipe 15 leading from a tank 16, the pipe 15 being controlled by a valve 17.

For admitting air into the combustion 50 chamber 10 and for controlling the flow of the air admitted, the combustion chamber 10 is provided with a circular opening 20 which is partly closed by a plurality of flat, triangular, fixed plates 21 which radiate 55 from the center of the opening 20. Within the chamber 10 and arranged to control the

openings between the plates 21 is a flat, circular damper 25 which is provided with a circular opening partly covered by a plurality of triangular plates 26 integral with 60 the damper and corresponding in size, number and arrangement with the fixed plates 21. The damper 25 is fixedly secured upon a horizontal shaft 30 which is arranged to 65 rotate about an axis coincident with its longitudinal axis and containing the center of the circular opening 20 through the wall of the chamber 10, and the damper 25 is so arranged that by rotating the shaft 30 through a variable arc, the effective areas 70 of the triangular openings through the chamber 10 may be correspondingly varied.

A segmental gear 31 is loosely mounted upon one end of the horizontal shaft 30 at a point outside of the chamber 10 and is 75 engaged by a vertical rack 32 the lower end of which engages loosely in and forms a core for a fixed solenoid 33. A spiral spring 35 surrounds the lower portion of the rack 32 and is arranged between the upper end of the solenoid 33 and a collar 36 which surrounds and is adjustably secured to the rack 33 by means of a set-screw 37, the collar 36 being adjustable longitudinally 80 of the rack 32 and normally held in such a 85 position with respect to the rack 32 as to cause the spring 35 to hold the rack 32 normally in its outermost position. Rigidly secured to the shaft 30 is a ratchet 39 which is 90 engaged by a pawl 27 pivotally secured to the gear 31 and held yieldingly in an operative position by a spring 38. The ratchet 39 is provided with four teeth and is so arranged that when the ratchet is in an initial 95 position of rotation, the damper 25 will be open to a maximum extent. When the ratchet 39 is rotated in a clockwise direction from its initial position, as viewed in Fig. 2 through one step or 90° the damper will 100 be partially closed, and when the ratchet 39 is rotated through a second step of 90° from its initial position the damper 25 will be again fully opened. During any number of succeeding steps the damper will be alternately fully opened and partially closed. 105

For energizing the solenoid 33 to rotate the damper 20 through a predetermined arc, one end of the solenoid 33 is connected by a conductor 40 to a fixed contact 41, and the other end of the winding of the solenoid 33 110 is connected by a conductor 42 to one pole of a battery 43 the other pole of which is

connected by a conductor 44 to a switch 45 which is arranged to swing about a fixed axis on a pivot 46 into and out of engagement with the contact 41, and is normally held out of engagement with the contact 41 by means of a spiral spring 47.

The switch 45 is controlled by a fixed electromagnet 48 which is in a circuit 49 which includes a battery 50 and which is controlled by a detector 51 of any well known or suitable construction. The detector 51 is arranged to be controlled by a closed oscillatory circuit which includes a coil 52 and a variable condenser 53, this closed-circuit being tuned to a given secondary frequency. The coil 52 forms the secondary of a transformer 54 which includes a primary coil 55 which is in a circuit 56 which includes a battery 57 and which is controlled by a detector 60 of any well known or suitable construction. The detector 60 is arranged to be controlled by a closed oscillatory circuit including a coil 61 and a variable condenser 62, and the coil 61 forms the secondary of a transformer 63 which includes a primary 64 one end of which is connected by a conductor 65 to a suitable ground 66 and the other end of which is connected to the lower end of an antenna 70 which is arranged to receive electroradiant oscillations from a distant station. The closed oscillatory circuit 61, 62 which is immediately controlled by the open aerial circuit including the antenna 70 is preferably tuned to respond to the natural frequency of oscillation of the open aerial circuit including the antenna 70, and the secondary frequency to which the corresponding closed oscillatory circuit 52, 53 is tuned is less than the natural frequency of oscillation of the open aerial circuit which includes the antenna 70.

In the operation of the form of this invention shown in Fig. 1 the gasolene burner 13 is kept burning continually with its flame directed downwardly upon the smoke producing material 11, and the damper 25 is given an initial adjustment as hereinbefore described which will permit a sufficient amount of air to enter the combustion chamber to cause in combination with the burner 13 a gradual and substantially complete combustion of the smoke producing material 11. When now it is desired to have smoke produced in the chamber 10 and delivered in large quantities through the chimney 12, an impulse of radiant energy having the desired high frequency and the desired secondary frequency impressed thereon is transmitted from the distant station and causes the electromagnet 48 to be energized as the result of the conjoint and successive actions of the two detectors 60 and 51, and this closes the circuit through the battery 43 and solenoid 33 and thus draws the rack 32 downwardly into its lowermost position to

rotate and to partly close the damper 25 accordingly to such an extent that the air which will be permitted to flow through the damper inwardly and to the combustion chamber 10 will not be sufficient for the complete combustion of the smoke producing material 11, and consequently large volumes of smoke will be produced which will be delivered outwardly through the chimney 12. If it should now be desired to stop the production of smoke a second impulse of radiant energy is sent which operates solenoid 33 and by means of the wheel 31 and ratchet 39 opens the damper 25 to allow a full supply of air and therefore complete combustion.

In the modified form of this invention shown in Fig. 3 the construction is the same as that shown in Fig. 1, and hereinbefore described, except that instead of having the combustion chamber 10 provided with a damper 25 for controlling the inlet of air, a flat, circular damper 75 is arranged in the chimney 12 and extends normally transversely thereof in such a manner as to almost but not entirely prevent the flow of the products of combustion therethrough from the combustion chamber 10. The damper 75 is rigidly secured to a horizontal shaft 76 which is arranged to rotate about a fixed axis coincident with its longitudinal axis and which is arranged to be oscillated by a segmental gear 77 rigidly secured to one end of the shaft 76 and arranged outside of the chimney to be engaged by a vertical rack 32 arranged to be operated as hereinbefore described by the solenoid 33 controlled in response to electroradiant energy.

In the operation of the modified form of this invention shown in Fig. 3 the arrangement is such that the damper 75 is normally in a substantially closed position which prevents any appreciable amount of smoke being delivered through the chimney 12, but when the electro-magnet 32 is energized in response to radiant energy as heretofore described the rack 32 is drawn downwardly and thus the damper 75 is rotated through 90° to permit the smoke to pass freely upwardly through the chimney 12.

In the form of this invention shown in Fig. 4 the construction is the same as that shown in Fig. 1, except that instead of having dampers provided, a ladle or container 100 is arranged within the combustion chamber 10 above the smoke producing material 11 and is fixed upon a horizontal shaft 101 which is arranged to rotate about a fixed axis coincident with its longitudinal axis. A segmental gear 102 is rigidly secured to the shaft 101 and is arranged outside of the combustion chamber 10 to be engaged by a vertical rack 32 which is arranged to be controlled by an electro-magnet 33 controlled by radiant energy as hereinbefore described.

In the operation of the modified form of

this invention shown in Fig. 4 the chamber 10 is partly filled with a suitable chemical or material 105, for instance with iodine or any other suitable material, and the ladle 100 is filled or partly filled with a chemical or mixture of materials 106, for instance with phosphorous or any other suitable material or materials which, when mixed with the material 105 in the combustion chamber, 5 will quickly produce a dense volume of smoke. Normally the ladle 100 is held in an upright position, and when it is desired to produce smoke, the solenoid 33 is energized in response to electroradiant energy as hereinbefore described and this causes the rack 32 to be drawn downwardly to rotate the ladle or receptacle 100 through an arc of about 180° to empty the contents of the ladle 100 upon the material 105 contained in 10 the lower portion of the chamber 10, whereupon the contents of the ladle 100 will unite with the material 105 to produce quickly large volumes of smoke which will be discharged through the chimney 12.

25 Having thus fully described this invention, I claim:

1. In a smoke producer, the combination with a combustion chamber provided with an opening, of means responsive to radiant energy for controlling the effective area of 30 said opening.

2. In a smoke producer, the combination with a combustion chamber provided with an opening, of rotary means for controlling 35 the effective area of said opening, and means responsive to radiant energy for controlling said rotary means.

3. In a smoke producer, the combination with a combustion chamber provided with 40 an inlet for air and with a burner for pro-

ducing combustion within said chamber, of means responsive to radiant energy for controlling said inlet.

4. In a smoke producer, the combination with a chamber provided with an inlet for air and with means for producing combustion, of a rotary damper controlling said inlet, and means responsive to radiant energy for rotating said damper to control the flow of air through said inlet and consequently the amount of combustion within 45 said chamber.

5. In a smoke producer, the combination with a combustion chamber, of means for producing combustion within said chamber, 50 rotary means for controlling the amount of smoke produced in said chamber, and means responsive to radiant energy for controlling said rotary means.

6. In a smoke producer, the combination with a combustion chamber, of means responsive to radiant energy for controlling the production of smoke within said chamber, said means including a rotary member 55 movable within said chamber to control combustion.

7. The combination with a combustion chamber, of means for controlling the production of smoke in said chamber including a reciprocatory rack, means responsive to 70 radiant energy for moving said rack in one direction, and a segmental gear arranged to be actuated by said rack, and means arranged to be oscillated by said gear to control the production of smoke within said 75 chamber.

Signed at New York, in the county of New York and State of New York, this 9th day of October A. D. 1917.

JOHN HAYS HAMMOND, JR.
